CUTTING MACHINE

Napoleon A. Monfils, Haverhill, Mass., assignor to
 United Shoe Machinery Corporation, Borough
 of Flemington, N. J., a corporation of New Jersey

Application September 14, 1939, Serial No. 294,873

10 Claims. (Cl. 12—17)

This invention relates to cutting machines and is illustrated as embodied in a machine for cutting slots in insoles for the reception of the end portions of straps designed to hold a sandal on the foot of the wearer. It is to be understood, however, that the invention and various important features thereof may have other applications and uses.

Heretofore, various methods have been employed in securing the end portions of sandal straps to the sandal insole, with results more or less satisfactory. While strap receiving slots in insoles have commonly been cut by hand operated tools, the operation is time-consuming and there is a lack of uniformity in the results obtained.

It is an object of this invention to provide a high speed machine for making slots of uniform character at selected points in the upper surface of a sandal insole for the reception of strap ends, which may be readily secured in said slots by means of a suitable cement.

It is a further object of the invention to provide an especially simple and inexpensive machine for making cuts or slots in work pieces at indicated points upon proper presentation of the work piece to the machine.

It is an important feature of this invention that a cutter block for co-operation with a knife or cutter is associated with gaging means adapted to locate a work piece, such as an insole, in proper position for a cutting operation. When in proper position a vertical edge portion of the insole engages both the gaging means and the cutter block so that the cutter, as it approaches the end of its stroke, cuts through the margin of the insole and makes a clean cut of the leather substance where the latter is backed by the cutter block. Preferably, and as shown, the cutter block yields against a spring the tension of which may be adjusted to insure optimum resistance of the cutter block against the thrust of the cutter. By having the cutter block yieldingly mounted at one side of the gaging means or in between spaced portions of the gaging means, the cutter in its operative stroke may pass beyond the plane of the gaging surface into engagement with an inclined surface on the cutter block and thereby insure that the strap receiving slot is cut through the edge of the insole.

Preferably and as shown, the cutter is movable through an orbital path, the return or idle stroke of the cutter being above the path of its operative stroke. In the described movements of the cutter, the chip cut from the insole is

lifted from the latter thereby insuring accomplishment of the intended result.

With the described and other features and advantages in view, the invention will now be described in detail in the specification and then pointed out more particularly in the appended claims.

In the drawing,

Fig. 1 is a view in side elevation of a cutting machine showing one embodiment of the invention;

Fig. 2 is a top plan view of the work supporting table together with a sectional view of gage members and a cutting block;

Fig. 3 is a section in a vertical plane extending longitudinally of the cutting block;

Fig. 4 is a detail of the cutter on a larger scale;

Fig. 5 is an enlarged sectional view through a portion of an insole showing the slot or groove made by the cutter; and

Fig. 6 is a detail view showing the path of the cutter.

In the illustrated machine, which is specially designed to cut slots in marginal portions of insoles, there is provided a table 10 for the support of the work, said table having gage lines 11 scored therein and carrying fixedly secured thereto gaging means comprising spaced members 12 (Figs. 1 and 2) against which an edge portion of a sole is pressed to locate the sole for a cutting operation. Conveniently, the table 10 with its gages 12 is slidably mounted in a supporting member 14 for adjustment from right to left, and vice versa, in Fig. 1, adjustment being secured by the screw-threaded member 16 rotatable in a bracket member 18 projecting downwardly from the lower surface of the table 10, said member 16 being axially immovable in the member 18 while being screwed into or out of a screw-threaded socket in the support 14.

Located between the gage members 12 is a cutting block 20 (Fig. 2), preferably of compressed fiber or of a soft metal alloy such as brass, to provide an end surface for co-operation with a cutter 22 in securing a clean cut through the peripheral edge surface of the sole. As shown most clearly in Fig. 3, the cutting block 20 is slidable on the surface of the table 10 and is secured to the forward end of a rod 24 slidably mounted in a member 26 screw threaded in a casing or guide member 28 rigidly secured to the table 10, as by brazing. Surrounding the exposed part of the rod 24 is a spring 30 abutting the block 20 at its forward end and the member 26 at its rear end, the said spring serving to hold 55

the cutting block 20 yieldingly in its normal position of rest in which its operative surface is projected into substantial alinement with the gaging surfaces of the gage members 12, as clearly indicated in Figs. 2 and 3. By adjustment of the threaded member 26, the tension of the spring 30 may be adjusted so that the cutter block 20 takes the thrust of the cutter 22 with sufficient resistance to insure clean cutting through all the leather fibers right up to the surface of the edge of the sole. For co-operation with the spring 30 in locating the cutter block in its position of rest, there is provided a shoulder on said block which engages an edge portion of the table 10, as clearly shown in Fig. 3. Conveniently, the cutting face of the block 20 is slanted upwardly and backwardly, as indicated in Figs. 2 and 3, for reasons hereinafter pointed out.

Means is provided for holding the work piece 20 against displacement during the cutting operation, said means comprising in the illustrated construction a pair of spring members 31 (Figs. 1 and 2) secured to opposite sides of the casing 28. These spring members 31, while self-adjusting 25 to work pieces of various thicknesses, press the work firmly against the table 10 as the latter rises during upward movement of the supporting member 14 under action of a spring 33, when the operator releases a treadle means (not shown) 30 connected to the table supporting post 35 by a link member 37 (Fig. 1).

As indicated in Fig. 1, and as most clearly shown in Fig. 4, the cutter 22 is trough-shaped with a cutting edge at 22a and other cutting edges at 22b perpendicular to the cutting edge 22a, whereby a chip is taken out of the upper surface of the sole to leave a slot in said surface to a depth which may be predetermined through vertical adjustment of the table 10 and its support 14. By suitable adjustment of the table 10, it is possible also to accommodate work pieces of a wider range of thicknesses. As indicated in Fig. 1, the cutter 22 is mounted in a square opening in a clamping stud 32 which is used to secure 45 the cutter 22 to its carrier member 34.

Vertical adjustment of the support 14, and hence of the table 10, is secured by proper manipulation of a knurled thumb nut 39 which is screw threaded on a rod member 41 and locked 50 in adjusted position by a lock nut 39a, the upper end of member 41 being rigidly secured to the table support 14, and the arrangement being such that the nut 39 engages the under surface of a bracket 43 having an opening for slidably 55 receiving the rod 41. Bracket 43 is rigidly carried between bearing members 45, 47 for the post 35, the said bearing members being rigid with frame 49 of the machine. Surrounding the post 35 at its upper end is the spring 33 located 60 between the under surface of the table support 14 and the upper surface of the bearing member 45, the said spring 33 being of such strength as to support the member 14, and hence the table 10, in work presenting position against the downward 65 ward thrust of the cutter, the arrangement being such that the spring 33 is compressed when the operator steps on the treadle to move the support 14 and the table 10 downwardly while a work piece is being shoved into position beneath 70 the spring fingers 31 and against the gage members 12.

To limit the downward movement of the table 10 and support 14, there is provided a toothed collar 53 screw threaded on the rod member 41 75 and held in adjusted position by a spring 55

adapted selectively to engage the teeth of the collar 53. It will be understood that the collar 53, when turned, changes its spacing with respect to the upper surface of the member 43, this spacing determining the extent of the downward movement of the post 35 and hence of the table support 14, when the treadle is depressed. This limitation on the downward movement of the work support contributes to the efficiency of the machine by reducing to a minimum the time necessarily involved in work support operations. As will hereinafter be pointed out the cutter 22 is continuously operated so that a work piece is slotted through operation of the cutter as soon as the said work piece is lifted into the path of the cutter through upward movement of the support 14 and table 10.

As illustrated, the cutter carrier 34 is operated by means designed to give the cutter movement in an orbital path, the said means comprising a link 36 pivoted at 38 to the cutter carrier 34 and at 40 in a slot in a head 42 supported at the forward end of an arm 44 overhanging the table 10 and integral with a post or standard 46. By adjustment of the pin at 40, a desired variation 25 in the path of the cutter (and therefore in the slot in the sole) may be secured. This standard 46 is shown as secured to the machine frame 49 which may be a bench or a column, whereby the machine is supported at a suitable height. 30 Mounted in the upper end of the post 46 is a shaft 48 having secured thereto an eccentric 50 about which passes an eccentric strap 52 integral with the cutter carrier 34. Upon rotation of the shaft 48 and eccentric 50 in the direction 35 of the arrow (Fig. 1), the cutter carrier 34 is reciprocated first in a direction to force the cutter into the upper surface of the sole and then into contact with the cutter block 20 to effect a gouging of a sole member 54, as shown at 56 in 40 Fig. 5. Toward the end of the working stroke in this orbital movement of the cutter 22, the cutter block yields against the spring 30 and the end of the cutter wipes upwardly along the slanted face of the operative end of the cutter block, 45 said slanted or inclined face of the block acting as a shearing surface in co-operation with the upwardly moving cutter, thus insuring a clean cutting operation and removal of the chip from the sole. On its idle or return stroke, the cutter 50 22 moves in a path somewhat above the path of its operative stroke. Preferably the shaft 48 will be driven continuously from any convenient source of power at a speed of about 750 R. P. M.

In operating the machine, the operator steps 55 on the treadle, thereby depressing the table a distance predetermined by the spacing between the adjustable member 53 and the top of fixed member 43. He then places a sole on the table 10 with an indicating mark in the sole margin 60 directly above one of the gage lines 11 scored in the surface of the table 10. The sole is then shoved firmly toward the gage members 12 until it is positioned by such gage members. Upon releasing the treadle, the sole is carried up to 65 the plane where it will be operated on by the continuously oscillating cutter. In passing, it may be noted that while it is desirable that the operator should operate the treadle and work support in properly timed relation to the travel of 70 the cutter, it is not necessary because no harm is done if the first cut is incomplete, since the next succeeding cut will perfect the slot or groove. The operator may then shift the sole to another position for a second cutting or gouging opera- 75

tion. Ordinarily the cutter will cut a slot of about $\frac{1}{4}$ " width. If a wider slot is desired the sole is shifted correspondingly and a second cut is taken, overlapping the first somewhat, to provide a wider slot. Due to the efficiency and simplicity of the operation, an operator may readily produce in rapid succession a number of slots in the sole, according to the indications carried by the latter. As the cutter supports are shown 10 adjusted in Fig. 1, including the position of the pin 40 in its slot, the cutter will make a slanting cut into the insole for about $\frac{3}{8}$ inch and then a substantially horizontal cut of about $\frac{3}{8}$ inch to and through the vertical edge of the sole, as shown 15 in Fig. 5. However, the parts, including the supports for the table and cutter, may be adjusted to perform cutting operations for other purposes. For instance, the adjustment may be such as to cut into the top surface of the sole 20 and come out with a slanting cut clear through the thickness of the sole, thus making a notch in the periphery of the sole.

Having described my invention, what I claim as new and desire to secure by Letters Patent 25 of the United States is:

1. In a machine for cutting slots in an unattached sole member, a work support upon which the sole is supported, a gage member having a surface against which a peripheral edge portion 30 of the sole is pressed, a cutting block having a surface for co-operation with a cutter, said surface being substantially in the plane of said gaging surface, a trough-shaped cutter, and means to operate the cutter to cause it to enter the upper surface of the sole and to travel through the substance of the latter to and through a portion of the peripheral edge surface of the sole, the cutter and the cutter block co-operating to insure clean cutting of the material whereby a 40 chip is removed from the sole leaving a slot in the upper surface thereof.

2. In a machine for cutting slots in an unattached sole member, a support for a sole, a gage member secured to said support to locate the sole for the cutting operation, a cutter block adjacent to the gage member and spring-pressed into operative position, a trough-shaped cutter to cut a slot in the sole and to co-operate with the cutter block in completing the removal of a 50 chip from the sole, and means to operate the cutter in an orbital path such that the cutter presses the cutter block back against the resistance of its backing spring and then wipes upwardly along the surface of the cutter block to insure clean cutting and to remove the chip from the sole.

3. In a machine for cutting slots in an unattached sole member, a table to support a sole to be operated upon, spaced gage members against 60 which a peripheral portion of the sole is pressed to locate the latter, a cutter block located between the gage members, a spring backing the cutter block and operative to hold it yieldingly with its cutter surface projecting substantially into the plane of the gaging surfaces of the gaging members, a trough-shaped cutter to co-operate with the cutter block, and means to operate the cutter to cause it to cut a slot in the surface of the sole and to penetrate through the peripheral edge 65 surface of the sole into contact with the cutter block, the extent of movement of the cutter being such as to force the cutter block backwardly from the plane of the gaging surfaces, thereby to insure clean cutting of the material 70 and separation of a chip from the sole.

4. In a machine for cutting slots in an unattached sole member, a table having a substantially horizontal surface to support a sole, a gage member to position the sole on the table by engagement with an edge portion of the sole, 5 a cutter block having a slanting face to engage an edge portion of the sole adjacent to the portion engaged by the gage member, a trough-shaped cutter to co-operate with the cutter block in cutting a slot in the sole and simultaneously 10 removing a chip from the sole in producing the slot, a carrier member for the cutter, a link pivotally supporting the front end of the cutter carrier from a point above the table, an eccentric for operating the cutter carrier in co-operation 15 with said link, whereby the cutter is given a back-and-forth movement in an orbital path above said table, and a spring backing the cutter block whereby said block co-operates with the cutter in securing a clean cut of the material 20 from the sole, the block then yielding further to permit the cutter to continue movement in its orbital path.

5. A machine of the character described comprising a work support, a trough-shaped cutter 25 movable in an orbital path, a gage having a surface for positioning a sole member with its margin in the path of the cutter, a cutting block, a spring backing the latter, said block having an inclined surface in the path of the cutter, 30 said block being normally held with its inclined surface projected into the plane of said gaging surface, and being retractable under pressure by said cutter as the cutting edge of the latter wipes upwardly along said inclined surface to 35 complete the cutting operation, and means for operating the cutter transversely of the sole margin through the substance thereof in the direction of the sole edge to remove a chip and to form a slot in the margin of the sole. 40

6. In a cutting machine, a table for supporting a work piece, a gage member to locate the work piece for a cutting operation, a cutter block associated with the gage member, a spring yieldingly backing the block, a trough-shaped cutter 45 co-operating with the cutter block, and means to operate the cutter in an orbital path so arranged that the cutter is caused to engage the work piece at a point within the periphery of the latter to initiate the cutting of a slot in 50 the work piece and then to continue in its movement until it contacts the block and forces it back to complete the cutting of the slot and the removal of a chip of material from the work piece through co-operation of the cutter and the movable cutter block. 55

7. In a cutting machine, a cutter, means for moving the cutter in an orbital path, a table to support a work piece, a gage member to position the work piece on the table, said table being movable toward and from the path of the cutter thereby to make adjustment for variations in the thickness of the work to be operated upon and the depth of the cut to be taken 65 therein, a cutter block having its operative surface located substantially in the same plane as the operative surface of the gage member so as to engage an edge portion of the work piece closely adjacent to the portion engaged by the 70 gage member, and spring means backing the cutter block to permit yielding of the latter against the thrust of the cutter whereby the cutter block co-operates with the cutter in securing a clean cutting of the material and then 75

yields to permit continuation of the movement of the cutter in its orbital path.

8. In a cutting machine, a table for supporting a work piece, a gage member to locate the work piece for a cutting operation, a cutter block associated with the gage member, a cutter co-operating with the cutter block, means to oscillate the cutter continuously toward and from the cutter block, the gage member and table co-operating to position the work piece so that the cutter is caused to engage the work piece at a point within the periphery of the latter to initiate the cutting of a slot in the work piece and then in co-operation with the cutter block to complete the cutting of the slot, spring means backing the work supporting table, means to adjust the table to determine the depth of cut for various thicknesses of work pieces, and means including said spring means for moving the table between work receiving and work presenting positions with respect to said oscillating cutter.
9. In a cutting machine, a cutter, a cutter block, means for oscillating the cutter continuously toward and from the cutter block, a table to support a work piece, a gage member to po-

sition the work piece on the table, said table being adjustable toward and from the path of the cutter thereby to determine the depth of cut for various thicknesses of the work pieces to be operated upon, a spring to support the table in work presenting position, and a post connected to the table, said post being movable downwardly to depress the table against the pressure of said spring to a work receiving position, release of the post being instantly followed by upward movement of the table to present the work piece in the path of the cutter.

10. In a machine for cutting a groove through the exposed surface of an unattached sole and to and through a peripheral portion thereof, a table for supporting a sole, a cutter shaped to cut a groove in the sole, operating means constructed and arranged to cause said cutter to enter the exposed surface of the sole and to emerge through the edge of the sole, and a gage having a pair of abutments disposed upon opposite sides of the path of said cutter for engagement with the edge of the sole for gaging the sole and also for supporting the sole against the thrust of said cutter.

NAPOLEON A. MONFILS.
